US0D1081638S

(12) **United States Design Patent** (10) **Patent No.:** **US D1,081,638 S**
(45) **Date of Patent:** **** Jul. 1, 2025**

(54) **PORTABLE ELECTRONIC DEVICE CASE WITH ATTACHABLE DISPLAY MODULE**

(71) Applicant: **Alo Beauty Corp**, Encino, CA (US)

(72) Inventors: **Rachel C. Levin**, Los Angeles, CA (US); **Zachary T. A. Aldridge**, Los Angeles, CA (US); **Aren A. Kaser**, Seattle, WA (US); **Joshua Bueseler**, Seattle, WA (US)

(73) Assignee: **Alo Beauty Corp**, Encino, CA (US)

(**) Term: **15 Years**

(21) Appl. No.: **29/884,771**

(22) Filed: **Feb. 15, 2023**

(51) LOC (15) Cl. **14-03**

(52) U.S. Cl.

USPC **D14/250**

CLAIM

The ornamental design for a portable electronic device case with attachable display module, as shown and described.

DESCRIPTION

FIG. 1 is a top, front, right-side perspective view of a portable electronic device case with attachable display module showing a first embodiment of our new design; FIG. 2 is a bottom, front, left-side perspective view thereof; FIG. 3 is a top, rear, left-side perspective view thereof; FIG. 4 is a bottom, rear, right-side perspective view thereof; FIG. 5 is a front elevational view thereof; FIG. 6 is a rear elevational view thereof; FIG. 7 is a left-side elevational view thereof; FIG. 8 is a right-side elevational view thereof; FIG. 9 is a top plan view thereof; FIG. 10 is a bottom plan view thereof; FIG. 11 is a top, rear, right-side perspective view thereof wherein the camera lens portion of an environmental cell phone is visible through the rear opening of the portable electronic device case with attachable display module;

FIG. 12 is a top, front, right-side perspective view thereof wherein the portable electronic device case with attachable display module is shown with an environmental cell phone; FIG. 13 is an exploded top, front, right-side perspective view of the portable electronic device case with attachable display module according to the first embodiment of our new design showing the portable electronic device case component and the attachable display module component separated for clarity of disclosure;

FIG. 14 is an exploded bottom, front, left-side perspective view of the portable electronic device case with attachable display module according to the first embodiment of our new design showing the portable electronic device case component and the attachable display module component separated for clarity of disclosure;

FIG. 15 is an exploded top, rear, left-side perspective view of the portable electronic device case with attachable display module according to the first embodiment of our new design showing the portable electronic device case component and the attachable display module component separated for clarity of disclosure;

FIG. 16 is an exploded bottom, rear, right-side perspective view of the portable electronic device case with attachable display module according to the first embodiment of our new design showing the portable electronic device case component and the attachable display module component separated for clarity of disclosure;

FIG. 17 is an exploded right-side elevational view of the portable electronic device case with attachable display module according to the first embodiment of our new design showing the portable electronic device case component and the attachable display module component separated for clarity of disclosure;

FIG. 18 is an exploded top plan view of the portable electronic device case with attachable display module according to the first embodiment of our new design showing the portable electronic device case component and the attachable display module component separated for clarity of disclosure;

FIG. 19 is an exploded bottom plan view of the portable electronic device case with attachable display module according to the first embodiment of our new design showing the portable electronic device case component and the attachable display module component separated for clarity of disclosure;

FIG. 20 is a top, front, right-side perspective view of a portable electronic device case with attachable display module showing a second embodiment of our new design;

FIG. 21 is a bottom, front, left-side perspective view thereof;

FIG. 22 is a top, rear, left-side perspective view thereof; FIG. 23 is a bottom, rear, right-side perspective view thereof;

FIG. 24 is a front elevational view thereof;

FIG. 25 is a rear elevational view thereof;

FIG. 26 is a left-side elevational view thereof;

FIG. 27 is a right-side elevational view thereof;

FIG. 28 is a top plan view thereof;

FIG. 29 is a bottom plan view thereof;

FIG. 30 is a top, rear, right-side perspective view thereof wherein the camera lens portion of an environmental cell phone is visible through the rear opening of the portable electronic device case with attachable display module;

FIG. 31 is a top, front, right-side perspective view thereof wherein the portable electronic device case with attachable display module is shown with an environmental cell phone;

FIG. 32 is an exploded top, front, right-side perspective view of the portable electronic device case with attachable display module according to the second embodiment of our new design showing the portable electronic device case component and the attachable display module component separated for clarity of disclosure;

FIG. 33 is an exploded bottom, front, left-side perspective view of the portable electronic device case with attachable display module according to the second embodiment of our new design showing the portable electronic device case component and the attachable display module component separated for clarity of disclosure;

FIG. 34 is an exploded top, rear, left-side perspective view of the portable electronic device case with attachable display module according to the second embodiment of our new design showing the portable electronic device case component and the attachable display module component separated for clarity of disclosure;

FIG. 35 is an exploded bottom, rear, right-side perspective view of the portable electronic device case with attachable display module according to the second embodiment of our new design showing the portable electronic device case component and the attachable display module component separated for clarity of disclosure;

FIG. 36 is an exploded right-side elevational view of the portable electronic device case with attachable display module according to the second embodiment of our new design showing the portable electronic device case component and the attachable display module component separated for clarity of disclosure;

FIG. 37 is an exploded top plan view of the portable electronic device case with attachable display module according to the second embodiment of our new design showing the portable electronic device case component and the attachable display module component separated for clarity of disclosure; and,

FIG. 38 is an exploded bottom plan view of the portable electronic device case with attachable display module according to the second embodiment of our new design showing the portable electronic device case component and the attachable display module component separated for clarity of disclosure.

The broken lines in FIGS. 1-38 are for the purpose of illustrating portions of the portable electronic device case with attachable display module, and environmental structure, that form no part of the claimed design.
